CARBURETOR FOR INTERNAL-COMBUSTION ENGINES

Carleton W. Gilmore, Pampa, Tex.; Mary Myrtle Gilmore, independent executrix of said Carleton W. Gilmore, deceased

Application May 31, 1951, Serial No. 229,009

8 Claims. (Cl. 261—14)

1

This invention relates to carburetors for internal combustion engines and particularly to carburetors for engines using liquid fuels having high vapor pressure, such as butane and propane, which fuels must be kept under pressures ranging from 30 pounds to 200 pounds per square inch, depending on the composition of the fuel and the temperature to which the fuel is subject in storage.

An object of this invention is to provide a simple, practical, and comparatively inexpensively-constructed carburetor to handle liquid fuels of high vapor pressure without vaporizing the fuel prior to its delivery to the carburetor.

Another object of this invention is to provide a carburetor suitable for handling liquid fuels of high pressure wherein the fuel-to-air ratio may be maintained substantially constant for various engine speeds and loadings, and wherein said ratio can be readily adjusted for fuels of different viscosities.

The invention consists in the construction and novel arrangement of parts, hereinafter fully described, illustrated in the accompanying drawings, and pointed out in the claims appended hereto. After considering the embodiment of the invention herein shown and described, persons skilled in the art will understand that various changes in the form, proportion and minor details of construction may be made, within the scope of the appended claims, without departing from the spirit and principle of the invention.

Fig. 1 is a vertical, sectional view of the carburetor of my invention;

Fig. 2 is a sectional view taken on the line 2—2 of Fig. 1;

Fig. 3 is a vertical, sectional view of the lower half of the carburetor at 90° to the plane of the section of Fig. 1;

Fig. 4 is a diagrammatic view of the carburetor and the manner in which it is connected to an engine in use.

Referring to the drawings, the embodiment of the invention therein shown comprises a carburetor having a shell or body portion including an upper part 1 and a lower part 2. These parts may have any desired external contour and are formed interiorly to provide the main fluid flow passage M through the carburetor when the parts 1 and 2 are assembled as shown. The parts 1 and 2 may be interconnected in any desired manner, and are shown for convenience with their meeting ends interfitting and overlapped and any convenient means, such as screws S may be employed for securing these parts together.

2

The part 1 is provided with conduit means 3 for delivering liquid fuel under pressure to the carburetor. As shown, the conduit 3 extends laterally through an opening provided in the wall 5 of the part 1, and is secured therein by a nut 5 screw threadedly attached to the protruding end 4 of the conduit. The end 4 of the conduit is adapted to be connected to a source of liquid fuel under pressure. The conduit 3 within the part 1 of the carburetor extends upwardly and then substantially radially of the fluid flow passage therethrough and is provided with a downwardly directed fuel discharge orifice 6. A valve tube 7 is secured to the conduit 3 in position to receive liquid fuel discharged through the orifice 6, by any convenient means such as the collar 8 surrounding and secured to the tube 7 and in turn attached to the conduit 3 as shown. The tube 7 extends downwardly from the conduit 3 and the open lower end 9 thereof receives a needle valve 10, the valve being supported in an upright position and disposed within the downwardly directed opening in the end of the tube 7. The needle valve 10 is mounted for axial movement within the discharge end of the tube 7 and for this purpose is secured to a plug 11 which may be screw threadedly or otherwise engaged in the lower end of a guide tube 12 which is in turn slidably mounted upon the tube 7. The plug 11 is provided with a plurality of fuel discharge passages 11a for discharging liquid fuel flowing from the tube 7 when the needle valve is open into the mixing chamber, to be later described. The tube 12 has secured thereto intermediate its ends a flow constricting body member 13. The member 13 may be secured to the tube 12 in any desired manner such as by means of a collar 14 secured by soldering or welding to both the member 13 and the tube 12. The flow constricting member 13 is positioned to extend transversely of the fluid flow passage M and is preferably in the form of a hollow, generally inverted conical body member provided with a downwardly directed opening 15 at the apex thereof. The needle valve assembly including the needle valve 10, the plug 11, the tube 12, and the flow constricting member 13 are movably mounted in operative relation with respect to the tube 7 by means of a coil spring 16 supported within the lower part 2 of the carburetor by means of a transverse bar 17 mounted therein for longitudinal adjustment by means of screw members 18 threadedly engaged with opposite ends of the bar 17 and having their heads 19 positioned externally of the part 2 and supported on shoulders 19a for ready access when adjustment of the bar 17 is required. As shown

more particularly in Fig. 3, the bar 17, at a point midway of its ends, is provided with an upstanding collar 20 and an axially disposed opening 21. The lower end of the spring 16 is supported on the bar 17 and surrounds the collar 20 while the upper end of the spring 16 is engaged with the inside surface 22 of the bottom portion of the hollow member 13 to thus urge the needle valve assembly upwardly to maintain the needle valve in its closed position under normal conditions.

A mixing tube 23 is positioned centrally of the fluid flow passage M through the carburetor, said tube surrounding the spring 16 and having its upper end somewhat above the lower end of the guide tube 12 and fuel discharge ports 11a. The tube 23 is provided at its lower end with diametrically opposed slots 24 to straddle the bar 17 and to permit relative movement between the bar and tube during adjustment of the bar 17 as previously described. The tube 23 is provided with a lateral branch 25 which, as shown, extends through an opening in the side wall of the part 2 of the carburetor and is secured within said wall in any desired manner, such as by soldering. The branch 25 terminates outside of the carburetor and is adapted for connection to a source of heated air such as an air jacket J on the exhaust manifold of an engine to which the carburetor is connected.

It is apparent, in view of the foregoing description, that the spring 16 normally tends to maintain the needle valve 10 in a fully closed position. In order to maintain the needle valve open when an engine to which the carburetor may be connected is idling, a lever 26 is provided, said lever being pivoted intermediate its ends to a depending arm 27 secured to or forming a continuation of the conduit 3 as shown more clearly in Fig. 1. The lever 26 is positioned so that the inner end 28 thereof is engaged with the collar 14 in the normally closed position of the needle valve. The opposite end of the lever terminates within a cavity 29 formed in the side wall of the part 1, and is there connected to a rod 30 extending through the side wall of the part 1. The rod 30 is connected to a diaphragm 31 positioned within a diaphragm chamber 32, said diaphragm chamber being secured to the side wall of the carburetor part 1 by any suitable means, such as screws 33. The diaphragm 31 divides the diaphragm chamber in two parts, and the part of the diaphragm chamber remote from the carburetor body is connected by means of a nipple 34, by means not shown, to the intake manifold of the engine, so that when suction is developed in the intake manifold, the diaphragm 31 moves outwardly to pull the rod 30 and thus rock the lever 26 in a direction to depress the inner end 28 thereof, to cause the needle valve 10 to open and admit fuel to the carburetor when the engine is idling. A spring 35 is mounted within the diaphragm chamber 31 and is arranged to exert pressure on the diaphragm 31 in a direction to maintain the lever 26 in position to permit valve 10 to close under normal conditions, as shown in Fig. 1. The force exerted by the spring 35 on the diaphragm 31 may be adjusted by a screw threaded member 36 bearing upon one end of the spring so that the extent of opening of the valve 10 during idling may be regulated. If desired, manual means may be provided for opening the needle valve for starting, and such means is shown as a pull rod 30a passing through the side wall of the carburetor part 1 and connected to the lever 26. Preferably, the necessary amount

of loose play is provided between the pull rod 30a and the lever 26 so that the operation of the lever 26 by the pull rod 30a will not interfere with the suction controlled operation of the lever by the rod 30.

The inside wall of part 1 of the carburetor body defining the passage M is shaped generally like the frustum of an upright cone, is generally circular in cross section, so that the cross sectional area of the passage increases in the direction of fluid flow through the carburetor. The member 13 is generally streamlined and is dimensioned with respect to the surrounding conical wall of part 1 of the carburetor to provide an annular air flow passage 37 which, as the valve is opened and the member 13 moves downwardly, increases in cross sectional area to admit correspondingly greater quantities of air. The preferred amount of movement of the needle valve from closed to fully opened position is at least $\frac{1}{2}$ inch and not over 2 inches for each 100 horsepower of the engine to which the carburetor is attached. The preferred increase in diameter of the inside wall of part 1 of the carburetor with in the stated operating range of the needle valve and the body 13 is about $\frac{1}{8}$ inch per inch of axial length, but may be varied considerably from this figure. It is apparent that the greater the diameter change per inch in axial length, the shorter the needle valve movement will be and the less accurately will the fuel-to-air ratio of the mixture be controlled. It has been found that by properly proportioning the slope of the inside wall of part 1 of the carburetor, the taper of the needle valve, the size of the needle valve opening, and the strength and length of the spring 16, a practically constant fuel-to-air ratio can be obtained for all engine operating conditions when the kind of fuel and its pressure are maintained substantially constant. As the fuel pressure is increased or as fuel of lower viscosity is used, more fuel will flow through the same opening of the needle valve and the resulting mixture becomes richer as the needle valve is opened as the result of more air being sucked through the carburetor as the engine load is increased. Therefore, the fuel should be supplied to the carburetor by a constant pressure pump P and the needle valve designed for the pressure chosen; the lower the pressure, the larger will the needle valve and valve opening need to be. When using liquid propane as fuel, it is preferred that the fuel pump have a constant discharge pressure of about 200 pounds per square inch regardless of the fuel tank pressure. At this high pressure, the diameter of the needle valve and the valve opening need be relatively small. However, a carburetor designed for propane fuel will also work satisfactorily on butane or gasoline or mixed fuels when they are pumped to it at the same or substantially the same high pressure. Any desired adjustments of the needle valve for fuel of greater viscosity and resultant smaller flow through the same needle valve opening can readily be made by decreasing the compression of spring 16 through the medium of the adjustment screws 18, as previously described.

As previously stated, the branch 25 of the mixing tube 23 is adapted for connection to a source of hot air such as a jacket associated with the exhaust manifold of the engine to which the carburetor is connected. It is desirable to have all of the air flowing into the engine to be filtered by the usual air filter which may be attached to the upper end of the part 1 of the carburetor in

a conventional manner, and to provide the upper part of the carburetor with an opening 38 in the wall thereof which may, by means not shown, be placed in communication with the hot air jacket previously referred to. By this means, the difference in pressure within the carburetor between the hole 38 and the branch 25 of the tube 23 will cause a flow of air through the hot air jacket from the point 38 to the branch 25. Thus, hot air is discharged from the branch 25 into the mixing tube 23. The hot air thus delivered to the mixing tube 23 divides, part of it going upwardly around the lower end of guide tube 12 to mingle with the liquid fuel issuing from the fuel ducts 11a and thereby warm and vaporize the same to thus inhibit the formation of ice at this point. The mixture of hot air and fuel passes upwardly into the hollow member 13 and thence downwardly and out of the opening 15 thereof to mix with the unheated air flowing downwardly through the main passage M of the carburetor. The other portion of heated air passes downwardly through the tube 23 and out of the open bottom thereof to mix with the fuel mixture flowing downwardly through the carburetor from the part 1 into the part 2 thereof.

From the foregoing description, it is apparent that the pressure differential existing on the upstream and downstream faces of the member 13 causes axial movement of this member within the carburetor to increase the opening of the needle valve when the load on the engine increases and that by proper design of the slope of the inner wall of the part 1 of the carburetor which surrounds the member 13, the annular air space 37 may be controlled in all positions of the valve to maintain substantially constant air-to-fuel ratio of the mixture for all engine loads when a given fuel is fed to the carburetor under a given pressure. It is also evident that the delivery of warm or heated air to the region in which the liquid fuel is discharged from the needle valve precludes the possibility of icing and at the same time insures a rapid and substantially uniform mixture of the air and discharged fuel. Furthermore, the adjustable mounting of the bar 17 provides a ready means for adjusting and controlling the pressure differential necessary to move the member 13 to open the needle valve in accordance with fuel viscosity.

If desired, suitable guide grooves 11a may be provided in the inner wall of the part 2 of the carburetor to receive the ends of the bar 17 and stabilize the bar during adjustment thereof.

Having thus described my invention, what I claim is:

1. A carburetor comprising a body portion provided with a main fluid flow passage therethrough, conduit means for delivering liquid fuel under pressure to said passage, said conduit means terminating in a discharge orifice positioned substantially axially of said passage and arranged to deliver liquid fuel thereto in the direction of fluid flow therethrough, a needle valve controlling flow of liquid fuel from said orifice, spring means resiliently urging said needle valve to closed position, valve control means including a fluid flow constricting member surrounding said fuel conduit means and disposed transversely of said fluid flow passage and extending radially into close proximity to but spaced from the inner wall of said fluid flow passage to thereby restrict the flow of incoming fluid to the annular space between the periphery of said fluid flow constricting member and the

adjacent inner wall of the fluid flow passage, said fluid flow constricting member being mounted within the fluid flow passage for movement longitudinally thereof in response to fluid pressure differential existing on its upstream and downstream faces, means operatively connecting said valve control means to said needle valve for moving the same to open position against the force of said spring as the fluid pressure differential increases, means defining a fuel mixing chamber open at opposite ends, one end of said fuel mixing chamber surrounding said fuel discharge orifice and terminating beneath said fluid flow constricting member and out of the path of fluid flow through said annular space, and conduit means for delivering heated air to said mixing chamber.

2. The carburetor described in claim 1 wherein in the main fuel flow passage of the carburetor includes a portion generally conical in form, generally circular in cross section, and increasing in cross sectional area in the direction of fluid flow, said valve control means including an inverted, conically shaped, hollow body member positioned co-axially within said conical portion of the main fluid flow passage to provide an annular fluid flow passage surrounding said hollow body member, and wherein the fuel discharge orifice and needle valve are positioned co-axially within said hollow body member.

3. The carburetor described in claim 2 wherein in said inverted, hollow, conical body member is streamlined to minimize turbulence in the air stream flowing around said hollow body member.

4. The carburetor described in claim 1 wherein in the valve control means includes an inverted, conically-shaped, hollow body member within which the needle valve and the fuel discharge orifice are axially disposed, said hollow, conical, body member being provided with an opening at the apex thereof, and wherein said fuel mixing chamber surrounds the needle valve and the fuel discharge orifice and discharges upwardly into said hollow body member.

5. The carburetor disclosed in claim 1 wherein means is provided for opening the needle valve for starting fuel flow comprising a lever member pivotally mounted within the carburetor and having one end thereof overlying said valve control means and engageable therewith when said lever is rocked on its pivot, and means operable from the exterior of the carburetor for rocking said lever to move the valve control means in a direction to open the needle valve to start flow of fuel into the carburetor.

6. The carburetor described in claim 1 wherein means are provided to maintain the needle valve in an open, idling position comprising a diaphragm chamber adapted for operative connection to the suction manifold of an engine, a diaphragm within said chamber, a lever pivoted within the carburetor and including an end portion overlying said valve control means and engageable therewith to open the valve when the lever is rocked on its pivot, and an operative connection between said diaphragm and said lever for rocking the lever in response to intake manifold suction on said diaphragm, to thereby hold open the needle valve for engine idling.

7. A carburetor comprising a body portion provided with a main fluid flow passage therethrough, conduit means for delivering liquid fuel under pressure to said passage, said conduit means terminating in a downwardly-directed, open-ended, axially-disposed, discharge portion, a tu-

tubular member slidably mounted on said discharge portion, said tubular member carrying an upwardly-directed needle valve projecting within the open end of said discharge portion of the conduit and controlling flow of fuel therefrom, means for supporting the needle valve comprising a bar disposed transversely of the main fuel passage of the carburetor, means for adjustably supporting the bar at any one of a plurality of longitudinally-spaced positions within the carburetor, a helical spring member supported at one end on said bar, a flow constricting member carried by said tubular member and extending therefrom transversely of the main fuel flow passage of the carburetor, said flow constricting member having a peripheral portion terminating in close proximity to but spaced from the inner wall of said fluid flow passage and restricting the flow of incoming fluid to the annular space between said member and the inner wall of said passage, the opposite end of said helical spring member engaging said flow constricting member from below and urging it and the needle valve upwardly to close the needle valve, a mixing chamber surrounding the open end of the discharge

portion of the fuel conduit, and means for discharging air from the mixing chamber upwardly around the needle valve and fuel discharge portion of the conduit means.

5 8. The carburetor described in claim 7 wherein said mixing chamber comprises an axially-disposed, tubular member open at its opposite ends and provided with a laterally-directed air intake means intermediate its ends, the opening in the mixing chamber at its lower end discharging secondary air into the fuel mixture flowing downwardly through the main fluid flow passage of the carburetor.
